(57) **CLAIM**

We claim the ornamental design for a double-tier pet furniture piece, as shown and described.

DESCRIPTION

FIG. 1 is a perspective view of a double-tier pet furniture piece according to a first embodiment of the design.

FIG. 2 is a first side view of the double-tier pet furniture piece of FIG. 1.

FIG. 3 is a first end view of the double-tier pet furniture piece of FIG. 1.

FIG. 4 is a second side view of the double-tier pet furniture piece of FIG. 1.

FIG. 5 is a second end view of the double-tier pet furniture piece of FIG. 1.

FIG. 6 is a top view of the double-tier pet furniture piece of FIG. 1; and,

FIG. 7 is a bottom view of the double-tier pet furniture piece of FIG. 1.

Portions shown in broken lines are for illustrative purposes only and form no part of the claimed design.
